[57] CLAIM

The ornamental design for a roof insulation stress-distribution fastener plate, as shown.

DESCRIPTION

FIG. 1 is a top plan view of the roof insulation stress-distribution fastener plate showing my new design;

FIG. 2 is a bottom plan view thereof;

FIG. 3 is a cross-sectional view taken in the direction of the arrows on line 3—3 of FIG. 1; and

FIG. 4 is a side elevational view thereof.
